UNITED STATES PATENT OFFICE.

WILLIAM GOELZ, OF ALBANY, NEW YORK.

VENTILATOR FOR LOCOMOTIVES.

1,097,858.

Specification of Letters Patent. Patented May 26, 1914.

Application filed January 14, 1914. Serial No. 812,068.

To all whom it may concern:

Be it known that I, WILLIAM GOELZ, a citizen of the United States, residing at Albany, in the county of Albany and State 5 of New York, have invented certain new and useful Improvements in Ventilators for Locomotives, of which the following is a specification, reference being had to the accompanying drawings.

10 This invention relates to new and useful improvements in ventilators and more particularly to ventilators for locomotive cabs and the primary object of the invention is to provide an improved ventilator which 15 may be adjusted to various positions to admit air into the cab, as desired by the engineer.

A further object of the invention resides in providing depending members on the 20 ventilator covers, with means in connection therewith to retain the covers in various adjusted positions and a still further object resides in providing a device which is simple and durable in construction, inexpensive 25 to manufacture and one which will be very efficient and useful in operation.

With these and other objects in view, the invention consists in the novel features of construction, combination and arrangement 30 of parts as will be hereinafter referred to and more particularly pointed out in the specification and claims.

In the accompanying drawing forming a part of this application, Figure 1 is a vertical longitudinal section through a cab having an adjustable ventilator construction applied to use therein and constructed in accordance with my invention. Fig. 2 is a vertical section as seen on line 2-2, Fig. 1. 40 Fig. 3 is a similar view as seen on line 3-3, Fig. 1.

In describing my invention, I shall refer to the drawing, in which similar reference characters designate corresponding parts 45 throughout the several views and in which 1 indicates a locomotive cab of the usual or any preferred design, the roof or top portion of which is provided with ventilator openings 2. Slidably mounted on the roof 50 or top of the cab to cover the openings, are the covering plates 3, forming adjustable covering means for said openings and, removably secured to the under face of each

of the plates 3, to depend therefrom, is a plate member 4. The lower portions of 55 these depending plate members 4 are slotted, as shown at 5, to form fork-like lower ends thereon, the purpose of which will be hereinafter and more particularly set forth.

As shown, a pair of covering plates 3 are 60 provided for a similar number of openings and disposed intermediate of the openings and secured to the top or roof of the cab, to depend therefrom, is a guide plate 6. This guide plate is provided with a pair of parallel slots 7 and the depending plates 4 are 65 so arranged, with respect to one another, and with respect to the slots of said guide plate, as to permit the slot of one plate 4 to align with one slot 7 and the slot of the other 70 guide plate to align with the other slot 7. A pin 8 is disposed through the furcations of each plate member 4 and, of course, is disposed through the slotted portion 5 thereof, and loosely pivoted on the pin of each plate 75 member, within said slotted portion 5 thereof, is an arm 9. The arms 9 are also loosely disposed through the slots 7 of the depending guide plate 6 and the extreme free ends of the same are bent angularly to form handle 80 members or the like 10. The lower edges of these arms 9 are also notched, as shown at 11, to afford a means for adjustable engagement with the lower edges of the slots 7 in the guide plate 6 to correspondingly adjust 85 the covering plates 3 with respect to the ventilator openings 2. In any position to which said arms may be adjusted, the same will be so held in view of the notches 11, being engaged with the lower edges of the slots 7. 90 In this manner, the air ventilating to the cab may be readily and quickly adjusted according to the desire of the engineer.

From the foregoing description of the construction of my improved device, the manner 95 of applying the same to use and the operation thereof will be readily understood and it will be seen that I have provided a device which is simple and durable in construction, inexpensive to manufacture and one which 100 will be very efficient in use.

While I have particularly described the elements best adapted to perform the functions set forth, it is obvious that various changes in form, proportion and in the 105 minor details of construction may be re-

sorted to without departing from the spirit or sacrificing any of the principles of the invention.

Having thus described this invention, 5 what I claim is:—

1. In a ventilating device of the class described, the combination with a housing having ventilating openings in the top thereof, and sliding closures for said ventilating 10 openings; of depending plates carried on said closures, an additional depending plate secured to the top of the housing intermediate of the openings, said plate being provided with a pair of slots, and a pair of arms 15 pivotally carried on the first mentioned depending plates and guided through the slots of the last mentioned depending plate.
2. In a ventilating device of the class described, the combination with a housing having 20 ventilating openings in the top thereof, and sliding closures for said openings; of depending plates carried on said closures, an additional depending plate carried on the top of the housing intermediate of the 25 ventilating openings therein, said last mentioned plate being provided with a pair of parallel slots, arms pivotally carried on the first mentioned depending plates and guided through the slots of said last mentioned 30 depending plate, handle members formed on the free ends of said arms, and means

formed on said arms adapted for coöperation with portions of the last mentioned depending plate to retain said closures in various adjusted positions.

3. In a ventilating device of the class described, the combination with a housing having ventilating openings in the top thereof, 35 sliding closures for said openings; depending plates carried on said closures and disposed in planes offset from one another, an additional depending plate carried on the top intermediate the openings therein, said last mentioned plate being provided with a pair of parallel slots alining respectively 40 with the first mentioned depending plates, arms pivotally carried on the lower ends of the first mentioned depending plates and guided through the slots of the last mentioned plate, the lower edges of the arms 45 being notched and adapted for engagement with the lower walls of the slots of the first mentioned plate to retain the closures in various adjusted positions, and handle members carried on the free ends of said arms. 50

In testimony whereof I hereunto affix my signature in the presence of two witnesses.

WILLIAM GOELZ.
